[57] **CLAIM**

The ornamental design for basketball telephone, as shown and described.

DESCRIPTION

FIG. 1 is a perspective view of my basketball telephone; FIG. 2 is a front elevational view thereof with a basketball earpiece in place on a basket;

FIG. 3 is a front elevational view thereof with the basketball earpiece removed from the basket;

FIG. 4 is a rear elevational view thereof;

FIG. 5 is a top elevational view thereof with the basketball earpiece in place in the basket;

FIG. 6 is a top elevational view thereof;

FIG. 7 is a right side elevational view thereof;

FIG. 8 is a left side elevational view thereof; and,

FIG. 9 is a front elevational view of a second embodiment of my basketball telephone the only difference being in the shape of the backboard.

The broken line disclosure throughout the views is for illustrative purposes only and forms no part of the claimed design.
